UNITED STATES PATENT OFFICE.

MARTIN B. MC LAUTHLIN, OF MALDEN, MASSACHUSETTS.

ELEVATOR CONTROL SWITCH.

Application filed September 17, 1921. Serial No. 501,487.

This invention relates to control switches for elevators which may be readily adapted for all types of electric power, employing direct or alternating current, for insuring that when the power circuit is interrupted while the switch is closed it may not be re-established without opening the control switch and then closing it. This provides against accidents liable to occur through unexpected starting of an elevator car after an interruption in the service if the controller should have been left in running position. For this purpose a main switch preferably of the magnetically closed no-voltage opening type is interposed between the service mains and the motor. This switch is initially closed by the closing of the circuit by the controller switch and is maintained closed so long as the current flows in this circuit. On failure of the current this main switch opens and the control circuit may not thereafter be closed to close the switch except by moving the controller switch to its "off" position and then closing it by moving it to its "on" position in one or the other direction. This switch also carries the contact arms for reversing the motor, these arms being actuated with the control circuit switch.

A further feature of this invention relates to the construction and mounting of these arms by which the switch is readily adjustable to various types of electric power.

This invention also provides a construction whereby the controller switch may be operated by a cable actuatable from the elevator car and which is able to withstand severe usage without being damaged.

For a more complete understanding of this invention, together with further objects and advantageous details of construction and combinations of parts, reference may be had to the accompanying drawings in which

Figure 1 is a plan of the controller switch in open position, the wiring connections being indicated in dotted lines, the supplemental contacts for the controller circuit being omitted for a clearer showing of other parts.

Figure 2 is a side elevation, the supplemental contacts being in position.

Figure 3 is an end elevation.

Figure 4 is a fragmentary section on line 4-4 of Figure 3 showing the supplemental contacts for the control circuit in top plan.

Figure 5 is a detail section on line 5-5 of Figure 2.

Figure 6 is a wiring diagram for a three phase power system.

Figures 7 and 8 are diagrams illustrating the application of this invention to a direct current system.

Figures 9 and 10 are diagrams further illustrating an application of the invention to alternating and direct current systems, respectively.

The controller is illustrated in Figures 1 to 5 and comprises a base member 1 in the form of a substantially rectangular shallow pan. At one end this base has an upstanding wall 2 having a substantially rectangular marginal flange 3 extending toward the opposite end of the base 1. The flange 3 is spaced inwardly from the edge of the wall 2 to form a socket for the reception of a cover member, not shown, which is adapted, with the pan 1, to enclose the switch elements 75 to be later described.

Extending inwardly from the wall 2 within the flange 3 is a boss 4 shown in dotted lines in Figures 1 and 2. This boss is centrally perforated and forms a bearing for a rock shaft 5. The lower end of the wall 2 has an outstanding bracket member 6 terminating at its outer upper end in a boss 7 which forms a second bearing for the shaft 5 spaced from the bearing 4.

Positioned between the bearings 4 and 7 is an actuating pulley or wheel 8 fixed to the shaft 5. This wheel 8 has marginal flanges 9 between which may be wound the actuating cable which passes lengthwise of the elevator shaft-way and which may be moved by the operator for the purpose of rocking the shaft 5 to make and break the control contacts as will later be described. This wheel 8 has a central web portion 10 having a boss 11 perforated for the reception of the shaft 5 and to which the shaft is made fast as by a set screw 12 (see Figure 1). The web 10 is cut away as shown at 13 in Figure 3 to an extent sufficient to allow the bracket 6 and the bearing 7 to be passed therethrough. The wheel is thus assembled on the shaft 5 with the bracket 6 extending through the cut-out 13, by which construction it is evident that the shaft 5 is limited to a partial rotation by the edges of the cut-out 13 impinging against opposite sides of the bracket. In order to cushion the blow imparted thereto the web 10 has a pair of sockets 14 for the reception of resilient plugs 110

15 engageable with opposite sides of the bracket 6 on the rocking of the shaft. At the point 16 is shown a flange near the outer circumference of the wheel arranged substantially parallel to the web 10, this flange and the web carrying therebetween a bolt 17 to serve as an anchoring means for the actuating cable. Bearings 4 and 7 furnish the sole support for the rock shaft 5, the free end of which extends over the pan 1 and to which switch arms may be attached.

As shown more particularly in Figure 5, the free end of shaft 5 is surrounded by an insulating sleeve 20 and is perforated at intervals as shown at 21 for the reception of insulating bushings 22. Through these bushings may be passed bolts 23 for securing switch arms 24 to rock with the shaft 5. The bolts pass through washers as 25 beyond which they may carry metal washers as 26 against which are placed lock washers as 27 held in place by nuts 28 threaded on the bolt ends. By this means the switch arms are made fast to the shaft 5 but thoroughly insulated therefrom.

The wall 2 adjacent its lower portion has a pair of inwardly extending bosses 30 which are perforated for the reception of rods 31. These rods 31 project substantially parallel to the shaft 5 and are preferably polygonal in cross section, being shown herein as square. These rods are preferably covered with a layer of insulation 32, as shown more clearly in Figures 2 and 3, and are adapted to carry spaced thereon contact elements 33 which may be clamped against rotation thereon. These elements may be of any suitable construction, but as herein shown each comprises a contact shoe 34 spring-supported by means of a coil spring 35 surrounding a guide pin 36 from an arm 37 which is bent to partially surround the bar 31 and which is clamped thereto by a mating member 37^a and tightening bolts 38 extending therebetween. These contacts are of usual construction and hence no detailed description is deemed necessary. At 39 are shown binding screws for attachment of wires to the member 37^a. The contacts 34 are preferably provided on opposite sides of the shaft 5 and in substantially horizontal alignment therewith, the arms 24 being adapted to contact therewith when in substantially horizontal position and to be out of contact therewith to maintain the switch open when in vertical position.

In order to retain the arms in these positions as desired a latch mechanism has been provided. This mechanism consists of a lever 40 pivoted at 41 to the wall 2 and extending downwardly beneath a collar 42 made fast on the shaft 5, this collar having a circumferential flange 43 partially enclosing the bearing boss 4. This flange 43 is formed with depressions 44 within which

may ride a roller 45 carried by the lever 40. This roller is urged against the flange 43 by means of a stiff spring 46 reacting between the free end of this lever and the base member 1, if desired guide lugs 47 and 48 being made fast to these parts for properly centering the spring.

The switch arms 24, above mentioned, are of two types, one of which is shown at 24' preferably arranged nearest the wall 2. Positioned diametrically opposite this contact arm is a similar arm 24', these arms being arranged to simultaneously contact with contacts 33 positioned on opposite sides thereof and one carried by each of the bars 31. These two contacts 24' are in electrical connection through the shaft 5 and furnish main switch elements in series with the no-voltage opening switch magnet, as will be later described. The remaining contact arms 24 are double, as indicated at 24^a, to bridge a pair of adjacent contacts 33 carried by one of the bars 31. These elements 24^a are staggered on opposite sides of the shaft 5 and insulated from each other, and are so positioned as to reverse the electrical connections therethrough when contacting with contacts carried by opposite bars 31. These elements furnish the reversing switch connections for the motor.

Positioned to be contacted by the arms 24' at certain times are a pair of supplemental contacts shown at 50 and 51. These contacts are similarly constructed but reversely arranged on opposite sides of the shaft 5 and positioned above the contacts 33. Each supplemental contact comprises a plate 52 of conducting material having a pair of arcuate slots 53 and 54 therein. Passed through these slots are pins 55 and 56 carried by a cross bar support 57, carried by a pair of posts 58 (see Figure 4) from a plate 59 which is made fast to a flange 60 depending from the upper outer edge of the flange 3. Each plate 52 has a slot 61 in its upper face and resting in these slots are opposite ends of a spring wire 62 which is fixed at its central portion at 63 to an insulating block and is in electrical connection to a binding screw 64 by which it is attached to a conductor 65. The lower end of the slot 53 is open, but the lower end of the slot 54 terminates at an inclined face 66 to which is made fast a strip of insulation 67. The slots 53 and 54 are sufficiently large to permit the block 52 to rock readily on either pin 55 and 56 as a center, the blocks being retained in position thereon by means such as washers 68 held in position by cotter pins 69 passed through the pins 56. These parts are so positioned relative to the switch arms 24' that when the shaft 5 is rocked to bring arms 24' from open position to closed position with contacts 33 as shown in Figure 7 in full lines, one of the blocks 50 or 51 will

be contacted on its conducting portion. For example, when the right hand arm 24' is approaching the right hand contact 37, the block 51 is impinged by the arm 24' along its inner surface, this block being rocked about the pin 56 as a center, the outer end of the block tilting upwardly about the pin 55 as shown. As the shaft 5 rocks sufficiently to bring the left hand arm 24' upward into contact with the left hand contact 33, the circuit is closed through this left hand contact, the arms 24' and the block 51 to the wire 65. Should the arm 24' be moved from closed to open position, as shown in dotted lines in Figure 7 at the left, the outer end of the arm 24' impinges against the insulating strip 67, rocking the block 50 upwardly about the pivot 55 as a center. As the insulation portion 67 is contacted, it is evident that electrical connection is not made between the contacts 37 and the block 50. This condition continues until the arms 24' are out of engagement with the contacts 33 whereupon the block 50 is rocked sufficiently to clear the end of the contact arm and drops downwardly into its idle position supported by both the pins 55 and 56, this action being facilitated by the resiliency of the spring wire 62. It is thus evident that when the shaft 5 is turned to bring the arms 24' from their off positions to their closed positions with the contacts 33, one or the other of the blocks 50 or 51 is brought into electrical contact therewith and that when the arms 24' are moved from closed to open position they fail to make electrical contact with either supplemental contact.

In Figure 6 is shown a diagram of the wiring connections by which this action of the arms and contacts is utilized. Referring to this figure at G is indicated diagrammatically a closing magnet for a no-voltage opening switch indicated at A. This switch is of any suitable type but as herein shown is of the three pole type and two poles are interposed in a pair of wires leading to the three phase motor M. At a and b and c are shown the wires leading to the three phase source of power. The leads a and b are adapted to be reversely connected to the phase windings of the motor in order to reverse the direction of the motor by means of the double contact arms 24'. Shunted across one of the phases of the motor is a circuit comprising the contact arms 24', the magnet G and one arm 70 of the switch A. When the switch A is opened, as when a no-voltage condition has occurred in this switch, the magnet G will fail to be energized through arms 24' and contacts 33 and the main switch will not be closed. It may, however, be closed by means of a supplemental circuit through the blocks 50 or 51 and the wire 65 shunting the arm 70 of the switch A. For example, suppose the switch arm is moved in a direction to contact and make electrical connection with the block 50, the circuit is completed from the right hand contact 33 to the arms 24', the block 50, the wire 65 through the magnet G and to the opposite phase wire, whereupon the magnet G is energized to close the main switch A. As soon as this is effected the motor is actuated and as the arms 24' continue to be moved and make contact across the mating contacts 33 current continues to flow through the magnet G maintaining the switch A closed. Similar action takes place when the rock shaft is moved to connect the motor in reversed relation except the block 51 is contacted instead of the block 50. Should the current to the motor be interrupted for any reason the switch magnet G immediately becomes de-energized and the main switch A opens. If then the voltage is again impressed on the lines a, b, and c, the blocks 50 and 51 being out of electrical connection, the magnet G remains de-energized due to the switch arm 70 being open. If the control shaft is rocked backwardly toward the open position of the switch, arm 24' contacts with the insulating portion of one or the other of these blocks, and fails to make shunt connection about the switch arm 70. The controller shaft may therefore be turned completely to off position without such contact having been effected. On subsequent motion thereof toward running position in either direction one or the other of the blocks 50 or 51 is contacted as above described to complete the circuit around the open switch 70 and through the magnet G to energize this magnet and close the switch A. If desired, interposed in the circuit to the magnet G are the elevator safety devices of any suitable or usual description at 71 such as a slack cable release, open door release, or the well switch which throws off the power when the car has traversed beyond its proper stopping place.

In Figures 7 and 8 is shown this device as designed for direct current systems. In this case the switch arms 24' are connected up to reverse the direction of current through the motor armature shown at M, a, the compound field windings being indicated at M, f. The line wires are indicated at d and e and at 72 is indicated a double pole switch. Shunted across the lines d and e is a circuit containing the magnet G for closing and holding closed the switch 72. This circuit may be closed either by bridging one of the supplemental contacts 50 or 51 with one of the adjacent contacts 33, the right hand contact 33 being chosen in the diagram, or by connecting across the contacts 33 by the arms 24'. When closed in the latter manner, however, a resistance 74 is interposed in the circuit, this resistance being of such a value as to permit sufficient current to pass to hold

the switch 72 closed but insufficient current to close this switch if it is open. This resistance is the equivalent of the switch arm 70 in Figure 6 since it acts to prevent the 5 closing of the main switch to the motor by bridging contacts 33 and necessitates connection previously through one of the supplemental contacts 50 or 51 for the switch to close and remain closed.

10 It is not essential that a double contact arm 24' be employed; Figures 9 and 10 indicating diagrammatically how a single arm 24' may be utilized in both alternating and direct current systems. In Figure 9 the control magnet G is in series with a circuit closed by the arm 24' between either contact 50 or 51 and its adjacent contact 33, the switch arm 70 in a shunt about these contacts being closed by the magnet G. When 15 the switch 70 is so closed by initial actuation of the magnet G through the arm 24', it maintains the magnet G energized so long as voltage exists across the lines. The magnet G also controls the main motor switch 20 (not shown) as before described.

In Figure 10 for direct circuit systems, a resistance is shown substituted for the switch 70 of Figure 9 and passes sufficient current to hold magnet G closed but insufficient current to close it when open. A 25 switch controlled by the magnet G might be used if desired, however, in place of the resistance in either of the direct current systems shown. Safety devices as 71 are shown 30 interposed in the magnet circuit G in the manner before described and at 75 is shown an accelerating device for cutting out resistances in the armature circuit to control the speed of the motor.

35 While this invention has been described in connection with the three phase and direct current systems, it is evident that it is also applicable to single or multi-phase systems of any type, it being only necessary to provide a sufficient number of reverse switch arms 24' properly connected in the motor circuit to reverse the motor, and the circuit for the no-voltage switch having an arm opened with the opening of the switch and 40 in circuit with the main switch contacts, and a by-pass for this arm controlled by the supplemental contacts and by which initial closing of the no-voltage switch may be effected. The construction of switch shown permits 45 the switch arms to be placed in position over the free end of the rock shaft without disassembling other parts. The contacts 33 may also be placed in position as desired without necessitating disassembling of the parts so 50 that it is a comparatively easy matter to assemble the arms and contacts as required for the particular system to which the controller switch is to be applied.

55 While as shown the no-voltage switch is closed by a magnet it is evident that

it might be otherwise controlled, it being only essential that the supplemental circuit actuated by the controller on moving it to closed position serves to initially close the no-voltage switch.

Having thus described certain embodiments of this invention it will be evident that many changes and modifications might be made therein without departing from its spirit or scope as defined by the appended 75 claims.

I claim:

1. A switch comprising a main contact, a supplemental contact having conducting and insulating portions, and a switch arm movable to impinge on said contacts serially, said arm contacting the conducting portion of said supplemental contact to close a circuit therethrough when impinging in one order of sequence, and contacting the insulated portion to maintain said circuit open when impinging in the reverse order.

2. A switch comprising a main contact, a switch arm movable to and from said contact to close and break electrical connection therewith, and a supplemental contact in the path of motion of said arm and having conducting and non-conducting portions, said conducting portion being contacted by said arm as said arm moves to close electrical connection with said main contact, and said non-conducting portion being contacted when said arm moves to break said connection.

3. A switch comprising a main contact, a switch arm movable to and from said contact to close and break electrical connection therewith, and a supplemental contact in the path of motion of said arm and having conducting and non-conducting portions, said conducting portion being contacted by said arm as said arm moves to close electrical connection with said main contact, and said non-conducting portion being contacted when said arm moves to break said connection, said supplemental contact being yieldable to permit said arm to move therewith.

4. A switch comprising a support, a bearing at one end of said support, a rock shaft journaled in said bearing and carrying a switch arm, contacts carried by said support and engageable by said arm, a wheel having an opening therethrough fixed to said shaft outwardly of said bearing, a bracket extending through such opening, and a bearing for the shaft outwardly of said wheel carried by said bracket.

5. A switch comprising a support, a bearing at one end of said support, a rock shaft journaled in said bearing and carrying a switch arm, contacts carried by said support and engageable by said arm, a wheel having an opening therethrough fixed to said shaft outwardly of said bearing, a bracket extending through said opening, a bearing for the shaft outwardly of said wheel carried by said

bracket, and bumping blocks carried by said wheel at opposite sides of said opening adapted to contact said bracket to limit the rocking motion of said shaft in opposite directions.

6. In combination, a support, a switch contact having a pair of pivotal connections to said support about either of which it may be turned, and a movable switch arm arranged 10 on movement in one direction to move said contact about one of said connections and on movement in the opposite direction to move said contact about the other of said connections.

15 7. In combination, a support, a switch contact comprising a plate having a pair of arcuate slots therein, a pin extending from said support through each of said slots and about either of which said plate may be 20 rocked, said plate having electroconducting and insulating portions, and a contact arm movable in one direction to impinge on said insulating portion and rock said plate about one of said pins, and movable in another direction to impinge on said conducting portion and rock said plate about the other of 25 said pins.

8. In combination, a support, a switch contact comprising a plate having a pair of 30 arcuate slots therein, a pin extending from

said support through each of said slots and about either of which said plate may be rocked, said plate having electroconducting and insulating portions, a contact arm movable in one direction to impinge on said insulating portion and rock said plate about 35 one of said pins and movable in another direction to impinge on said conducting portion and rock said plate about the other of said pins, and means for normally holding 40 said plate in one position.

9. In combination, a support, a switch contact comprising a plate having a pair of arcuate slots therein, a pin extending from said support through each of said slots and about either of which said plate may be rocked, said plate having electroconducting and insulating portions, a contact arm movable in one direction to impinge on said insulating portion and rock said plate about 45 one of said pins and movable in another direction to impinge on said conducting portion and rock said plate about the other of said pins, and a spring bearing on said plate and urging it to a position with each 50 of said pins contacting one end of the corresponding slot.

In testimony whereof I have affixed my signature.

MARTIN B. McLAUTHLIN.
